UNITED STATES PATENT OFFICE.

EDMUND B. WEDMORE, OF RUGBY, ENGLAND, ASSIGNOR TO GENERAL ELECTRIC COMPANY, A CORPORATION OF NEW YORK.

OIL-SWITCH.

1,115,264.

Specification of Letters Patent.

Patented Oct. 27, 1914.

Application filed July 11, 1908. Serial No. 443,075.

To all whom it may concern:

Be it known that I, EDMUND B. WEDMORE, a subject of the King of Great Britain, residing at Rugby, England, have invented certain new and useful Improvements in Oil-Switches, of which the following is a specification.

My invention relates to electric switches, and more particularly to oil switches arranged to open automatically upon the occurrence of abnormal current through the switch.

The object of my invention is to provide an automatic oil switch which may if desired be tripped by means of an operating handle and thereby opened with a quick break; in which the trip coils are directly connected to the terminals and yet may be calibrated without exposing the operator to danger; in which the contacts automatically assume the proper position to make the best engagement with each other, and in which a removable oil tank is automatically locked in position around the contacts by lifting it into inclosing position.

In carrying out my invention the operating mechanism of the switch preferably comprises two relatively movable members, one being a handle which is grasped by the operator and which also controls the latching means for holding the switch closed, while the other member is connected to the actuating toggle of the switch. The handle may be pivoted to the other member, and during the closing movement of the switch is rigid with the other member until the switch is locked in the closing position, while a movement of the handle to open the switch causes the release of the latching mechanism and permits the switch to open. The trip coils are connected directly in series with the switch, preferably by mounting them on one of the fixed terminals of the switch, and since the various parts of the trip coil may be at the potential of the terminal of the switch, the operator is protected from accidental contact with the trip coils by mounting them behind the insulating panel on which the switch is carried. In order to enable the trip coils to be adjusted without danger to the operator, a calibrating device extends through the panel into a position where it may be easily reached by the operator without coming into dangerous proximity to the trip coil.

The proper engagement of the contacts is insured by making the contacts automatically self-aligning by supporting one of each pair in a manner which permits it to rock in all directions about its point of support during the closing of the switch, to yield under spring pressure to a certain extent, thereby insuring proper engagement. The oil tank is automatically locked in inclosing position by means of any suitable automatic latching mechanism which is brought into latching position merely by the movement of the tank into engagement with the frame. In the preferred construction pivoted members on the tank slide into engagement with lugs on the frame and thereby lock the tank in position.

My invention will best be understood in connection with the accompanying drawings, which are merely illustrations of one of the various forms of switch in which it may be embodied, and in which—

Figure 1 is a longitudinal section of a switch embodying my invention; Fig. 2 is a view in elevation, showing the operating mechanism and calibrating device, Fig. 3 is a cross-section at right angles to Fig. 1, showing the contacts and the automatic latching mechanism for the oil can in elevation; Fig. 4 is a view of the actuating and locking toggles when in a collapsed position; Fig. 5 is a detail view showing the actuating toggle and the indicator in the position taken by it when the toggle collapses; and Fig. 6 is a top view of the actuating mechanism shown in Fig. 4.

In the form of switch shown in the drawings a frame or support 1 carries the fixed line terminals or contacts 2 mounted in any suitable insulators, and connected when the switch is closed by bridging contacts 3 moved relative to the terminals 2 by any suitable actuating mechanism. In the form shown in the drawings vertical actuating rods 4 are connected at one end to the bridging contacts and at the other end to a crosshead 4'. Actuating levers 5 are pivoted to the frame 1 at one end and are slotted at the other end to engage crosshead 4'. The levers 5 are moved by means of an actuating toggle comprising links 6 connected to the levers and corresponding links 7 pivoted to the frame, the links being joined by the pivot or pin 8. When the actuating toggle is straightened the parts

assume the position shown in Figs. 1 and 2 and the switch is closed, while the collapse of the actuating toggle permits the bridging contacts 3 to drop out of engagement with the terminals 2, thereby opening the circuit.

In the preferred embodiment of my invention the switch is made automatic and is mounted on one side of an insulating panel or support 9 of marble or other suitable material, the operating mechanism for the switch being mounted on the other side of said panel. The operating mechanism or handle preferably comprises a member 10 pivoted to the panel and connected to the actuating toggle of the switch, and a handpiece or handgrip 11 mounted integrally with a sector-shaped web 12^a, the web 12^a being integral with a shaft 13^a, which is, in turn, journaled in the member 10. By this construction the handpiece 11, the web 12^a and the shaft 13^a move as a unit, irrespective of the member 10. The web 12^a is provided with lugs 12 and 12' adapted to engage the member 10 and thereby limit the relative movement of the handpiece 11 and the member 10. The handpiece 11 also controls latching mechanism by means of which the switch is held in closed position and in the form shown in the drawings, this latching mechanism comprises a bolt or catch 13 mounted integral with the shaft 13^a and in such a position as to co-operate with a lug or projection 14 on the panel 9. The catch 13 is swung out of and into engagement with the projection 14, as the handpiece 11 is swung to the right or left, due to the fact that when the handpiece 11 moves, the integrally related shaft 13^a, journaled in the member 10, rotates and in rotating, the catch 13, which is also integral with the shaft 13^a, is forced up or down. A spring 15 tends to maintain the handpiece 11 and catch 13 in latching position, as shown in Fig. 2, with lug 12' in engagement with the member 10.

When it is desired to open the switch by the handpiece 11, it is pulled toward the operator and with it is moved the web 12^a. The shaft 13^a being in integral relation with both and journaled in the member 10, rotates in its bearing, the handpiece 11 and web 12^a therefore moving independently of the member 10. As the catch 13 is also in integral relation with the shaft 13^a, it is simultaneously moved with the handpiece 11 until it finally swings out from the projection 14, thus releasing the member 10 and unlocking the switch. Further movement of the handpiece 11 brings the lug 12 into engagement with the member 10 and allows the switch to be opened, the handpiece 11 and member 10 then moving as a unit.

The member 10 of the operating mechanism may be connected to the actuating

toggle in any suitable manner, but preferably through some collapsible connection, such as a toggle, which normally forms a positive connection between the member 10 and the actuating toggle, but may be broken by any suitable trip mechanism to trip the switch free from the handle and thereby permit the actuating toggle to collapse. In the preferred form of connection, as shown in Fig. 2, links 16 are connected at one end to the member 10, and have at the other end slots for the pin or pivot 8 of such length, as shown in Fig. 1, that the actuating toggle may collapse even though the member 10 and the links 16 remain in switch closing position. A normally positive collapsible connection is established between the links 16 and the actuating toggle by means of a locking toggle consisting of two parallel toggle links 17 pivotally mounted on the pin or pivot 8 and co-operating with toggle link 18 pivotally mounted between the links 16. The toggle links 17 are connected by a roller 19 which is normally held in the recess or depression 20 of the toggle link 18 by means of a retaining block 21 and when so held forms the pivot of the locking toggle between the links 16 and the actuating toggle of the switch. As shown in Figs. 1 and 4, the toggle link 18 is provided at its free end with laterally projecting pins 22, engaged by catches 23 which are pivotally mounted on the pin or pivot 8, and normally hold the toggle links 17 and 18 immovable with relation to each other. Each catch 23 is controlled by its tripping coil in any suitable manner, preferably by means of a tail piece 24 upon the upper edge of which rides a roller 25 of a movable tripping member 26 preferably made of some light insulating material. The parts are so proportioned that when the tripping members are lifted they engage and lift the tailpieces 24 while ordinarily they are suspended from the tail pieces by the rollers 25. By the lifting of the tailpieces 24 the catches 23 are moved out of engagement with the pins 22, and the locking toggle 17, 18 may collapse, the parts moving into the position shown in Figs. 4 and 6 and permitting the switch to trip free from the handle and open regardless of the position of the operating mechanism.

Fig. 4 shows the position of the locking toggle and the actuating toggle after the switch has been tripped by the overload coils, while the operating handle still remains in its closed position.

Any suitable form of trip coil or other electro-responsive tripping mechanism may be used; but the preferred construction is that shown in Fig. 1, in which the tripping mechanism for each catch 23 comprising an iron yoke or frame 27 mounted on the framework of the switch and forming part 130

- of a magnetic circuit which includes a movable armature or core 28 arranged to actuate the tripping member 26 and thereby collapse the connection between the handle and the switch. The movement of the cores are rendered dependent upon the electrical conditions in the circuit by means of series coils 29 surrounding the cores and carried upon the terminals 2, as shown in Fig. 3. By means of this construction the expense of a current transformer is avoided, since the series coils 29 are insulated from the rest of the switch by the insulator which carries the terminal 2 and by an air gap or other dielectric between each coil and its core. The lower end of each core 28 forms a right angle which projects through the insulating lining 45 as shown in Fig. 1. Attached to these projecting ends are foot members 44 which force members 26 upward when the plungers or cores 28 are drawn up by an overload coming upon the lines. In the preferred construction, the members 26 are of tubular construction with their upper ends slotted to such a length that rollers 25 are mounted between the sides of the slotted portions, while tailpieces 24 are inserted between the rollers and the bottom of the slots. There should be but little room between each tailpiece 24 and the bottom of its slot as the overload tripping calibrations partly depends upon the amount of movement of members 26 before the switch trips out.
- Where high potential is used the operator should be protected from accidental contact with the switch terminals and the series coils, which are preferably mounted, as shown in Fig. 1, behind and on the opposite side of the panel from the operating mechanism; and some suitable calibrating mechanism for the coils is provided which extends through the panel and enables the operator to calibrate the coils without coming into contact with them. Various arrangements for securing this result may be used; the preferred construction being a pivoted lever 30 mounted on the frame 1 and provided at one end with a projection 31 which engages the members 44 to regulate the position of the plungers, and at the other end with any suitable calibrating arrangement 32 mounted on the front of the panel and 55 preferably insulated from the projection 31, so that potential on the cores will not be transmitted to the operator.
- As best shown in Fig. 3, the contacts are made automatically self-aligning to insure the maximum surface of contact between them by providing each terminal with confronting contacts 33 connected to the terminal through any suitable flexible connections and normally moved toward each other by 65 a yielding support, preferably a leaf spring
- 34, the end of which is curved to engage a recess 35 in the back of the contact. This recess which is considerably larger than the spring, forms in effect a ball and socket joint with the spring and enables the contact to rock in all directions about the end of the spring as a pivot. The bridging contact 3 is made in the form of a wedge, and when the switch is closed enters between the contacts 33, spreading them apart and making a firm engagement with them.
- The placing of the oil can in position to inclose the contacts is facilitated by means of an automatic latching arrangement for securing the oil can to the frame 1 when the can is lifted into inclosing position. The automatic latching mechanism may assume various forms, and in the construction shown in the drawing comprises lugs 36 mounted on the frame 1 and each provided, as shown in Fig. 3, with an inclined surface. These lugs coöperate with spring-pressed bolts 37, provided with wing nuts 38 and pivoted to the oil can by pivots 39. A coiled spring 40 tends to force the bolts into the position shown in Fig. 3, and as the oil can is lifted into inclosing position, the wing nut 38 slides up the inclined surface of the lug 36, and finally, when the can is in the proper position, is forced, by the spring 40 into the locking position shown in Fig. 3, automatically latching the can to the frame. As a result of this construction, all that is necessary to lock the can in position is to lift it into contact with the frame.
- In a switch of this type, which may be opened either by hand or automatically, it is desirable to have some kind of an indicating device to show how the switch was last opened, and for this purpose I rotatably mount on the pin 46 a movable indicator 41, which is controlled by the collapse of the actuating toggle of the switch in any suitable manner, preferably through a rod 42 connected at one end to the pin or pivot 8, and with its other end in a position to engage the indicator 41 and move it out, as best shown in Fig. 5, when the actuating toggle collapses, thereby showing that the switch has tripped automatically.
- My invention may be embodied in many other forms than that shown and described, and I do not limit it to the precise arrangement disclosed, but intend to cover by the appended claims all changes and modifications within the spirit and scope of my invention.
- What I claim as new and desire to secure by Letters Patent of the United States, is,
1. In an electric switch, the combination with an actuating mechanism comprising a movable member, an operating member for moving said movable member, a normally positive collapsible connection between said members comprising two links connected to

125
130

said members respectively and in pivotal engagement with each other near the middle of one of said links, and restraining means mounted on a common pivot with one of said links to engage the free end of the other of said links and normally hold said links in substantial alinement and thereby enable said connection to transmit the thrust of one member to the other.

10 2. In an electric switch, the combination with a pivoted member and an operating member for moving said pivoted member, of a locking toggle between said members comprising a link pivoted to one of said members and provided with a notch near the middle thereof, a second link pivoted to the other member and in pivotal engagement with said notch in said first member, and latching means mounted in pivotal relation
15 with one of said members to engage the free end of said first link and thereby normally prevent the collapse of said locking toggle.

3. In an electric switch, the combination with a movable switch actuating member and an operating member for moving said switch actuating member, of a locking toggle between said members comprising a link pivotally mounted on said operating member and provided near the middle with a notch, a second link pivotally connected to said switch actuating member and provided at the free end with a roller fitting into said notch in said first link, and a latch mounted on the pivot of said second link to normally engage the free end of said first link and thereby prevent collapse of said toggle by the thrust transmitted through said toggle from the said operating member to said switch actuating member.

40 4. In an electric switch, the combination with a movable switch actuating member and an operating member for moving said switch actuating member, of a normally positive collapsible connection between said members comprising a locking toggle normally under set and bodily movable with

45

said members, a latch mounted in pivotal relation with said locking toggle to normally prevent collapse of said connection, said latch being provided with an extension in the direction of bodily movement of said toggle, and a tripping member loosely mounted on said extension and suspended therefrom in a position to bias said latch to latching position. 50 55

5. In an oil switch, the combination with coöperating contacts, an operating mechanism for actuating said contacts, a normally positive collapsible connection between said mechanism and said contacts, and automatic tripping means for controlling said connection, of an indicator movably mounted on said operating mechanism, and means mechanically actuated by the collapse of said connection to move said indicator and show the automatic opening of said switch. 65

6. In an electric switch, the combination of a switch member and an actuating member mounted to move relatively to each other, of a normally positive collapsible connection between said members, an indicator mounted on one of said members, and mechanical actuating means responsive to the collapse of said connection for moving said indicator. 70

7. An electric switch comprising a switch member and an actuating member mounted to move relatively to each other, of a normally positive collapsible connection between said members, an indicator movably mounted on one of said members, and a rod for operatively connecting said indicator and the other of said members to move said indicator in response to relative movement of said members due to collapse of said connection. 75 80 85

In witness whereof, I have hereunto set
my hand this second day of July, 1908.

EDMUND B. WEDMORE.
